UNITED STATES PATENT OFFICE

150,478

DESIGN FOR A BABY RATTLE OR THE LIKE

Herman Wapnick, Brooklyn, N. Y.

Application August 1, 1946, Serial No. 132,171

Term of patent 3½ years

(Cl. D34—15)

To all whom it may concern:

Be it known that I, Herman Wapnick, a citizen of the United States, residing at Brooklyn, New York, in the county of Kings and State of New York, have invented a new, original, and ornamental Design for a Baby Rattle or the like, of which the following is a specification, reference being had to the accompanying drawing, forming a part thereof.

In the drawing:

Fig. 1 is a front elevational view of a baby rattle or the like, showing my new design;

Fig. 2 is a side elevational view; and

Fig. 3 is a rear elevational view of the same.

I claim:

The ornamental design for a baby rattle or the like, as shown.

HERMAN WAPNICK.
